UNITED STATES PATENT OFFICE.

FREDRICK L. WOOLEY, OF CINCINNATI, OHIO, ASSIGNOR OF ONE-THIRD
TO JAMES H. GODMAN, OF CINCINNATI, OHIO.

NECKTIE-HOLDER.

SPECIFICATION forming part of Letters Patent No. 766,408, dated August 2, 1904.

Application filed February 15, 1904. Serial No. 193,716. (No model.)

To all whom it may concern:

Be it known that I, FREDRICK L. WOOLEY, a citizen of the United States, residing at Cincinnati, (Hyde Park,) in the county of Hamilton and State of Ohio, have invented certain new and useful Improvements in Necktie-Holders; and I do declare the following to be a full, clear, and exact description of the invention, such as will enable others skilled in the art to which it appertains to make and use the same.

This invention relates to improvements in necktie-holders.

The object of the invention is to provide a necktie-holder which may be quickly attached to and removed from a tie and which may be easily applied to a collar-button to securely hold the tie in place.

With this and other objects in view the invention consists of certain novel features of construction, combination, and arrangement of parts, as will be more fully described, and particularly pointed out in the appended claim.

In the accompanying drawings, Figure 1 is a rear view of a bow-tie, showing the application of the holder to the same. Fig. 2 is a front view of a portion of a collar and shirt, showing the manner of attaching the holder to the collar-button. Fig. 3 is a detail perspective view of the holder. Fig. 4 is a top plan view of the holder. Fig. 5 is an end elevation of the same.

Referring more particularly to the drawings, 1 denotes the holder, which is constructed from a single piece of spring-wire bent to form a button-engaging eye or loop 2 and laterally-projecting tie-engaging loops 3, which are disposed in a horizontal plane or at right angles to the plane of the eye or loop 2. The ends 4 of the wire after forming the loops 3 slightly overlap each other and are pointed, as shown.

The button-engaging loop is here shown as being substantially triangular in shape; but it is obvious that the same may be formed in various other shapes.

To use the holder, the same is attached to the back of a tie by engaging the pointed ends 4 with the fabric forming the same, as shown in Fig. 1. The ends of the loops 3 are now pressed together, which will open the eye or loop 2 and permit the same to be engaged over the head of a collar-button, and when the pressure on the loops 3 is released the loop 2 will retract and engage the shank of the button, as shown in Fig. 2, and thereby hold said loop in place and support the tie.

While the device is here shown as applied to a bow-tie, it is obvious that the same may be employed in connection with any form of tie and when desired may be quickly removed from one tie and applied to another, so that one holder may serve for a number of ties.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

A necktie-holder comprising a single piece of wire bent intermediate of its length and crossed to form a button-engaging loop or eye and having its ends extending in opposite directions beyond the eye and thence bent to form loops disposed at right angles to the eye, and provided with overlapping terminal points, substantially as described.

In testimony whereof I have hereunto set my hand in presence of two subscribing witnesses.

FREDRICK L. WOOLEY.
